(57) **CLAIM**

The ornamental design for a blood collecting device, as shown and described.

DESCRIPTION

FIG. 1 is a perspective view of a blood collecting device in accordance with the ornamental design;
FIG. 2 is a front view of the blood collecting device;
FIG. 3 is a back view of the blood collecting device;
FIG. 4 is a bottom view of the blood collecting device;
FIG. 5 is a top elevational view of the blood collecting device;
FIG. 6 is a right side view of the blood collecting device; and,
FIG. 7 is a left side view of the blood collecting device. The features shown in broken lines depict portions of the blood collecting device and form no part of the claimed design.
